US00D616240S

(12) **United States Design Patent**
Kostyun et al.

(10) **Patent No.:** **US D616,240 S**
(45) **Date of Patent:** ** *May 25, 2010

(54) **MEDIA HOLDER**

(75) Inventors: **James Kostyun**, Pittsfield, MA (US);
Kenny Freitag, Cheshire, MA (US)

(73) Assignee: **MeadWestvaco Corporation**,
Richmond, VA (US)

(**) Term: **14 Years**

(21) Appl. No.: **29/322,049**

(22) Filed: **Jul. 29, 2008**

(51) LOC (9) Cl. **06-04**

(52) U.S. Cl. **D6/634**

(57) **CLAIM**

The ornamental design for a media holder, as shown and described.

DESCRIPTION

FIG. 1 is a top plan view of a media holder;

FIG. 2 is a front view the media holder of FIG. 1 in a closed configuration; the back view being a mirror image;

FIG. 3 is a front view of the media holder of FIG. 1 in an open configuration; the back view being a mirror image;

FIG. 4 is a left side view of the media holder of FIG. 1;

FIG. 5 is a right side view of the media holder of FIG. 1;

FIG. 6 is a bottom plan view of the media holder of FIG. 1;

FIG. 7 is a plan view of the inside of the media holder of FIG. 1;

FIG. 8 is a top perspective view of the media holder of FIG. 1 in a closed configuration; and,

FIG. 9 is a perspective view of the inside of the media holder of FIG. 1 in an open configuration.

The broken line showings are included for the purpose of illustrating environment and form no part of the claimed design.

1 Claim, 7 Drawing Sheets
